DESIGN.

W. CHURCHILL.

HEADLIGHT COVER GLASS.

APPLICATION FILED OCT. 18, 1917.

52,384.

Patented Sept. 10, 1918.

William Churchill ^{Inventor}
Drey & Lee ^{Attorney}

UNITED STATES PATENT OFFICE.

WILLIAM CHURCHILL, OF CORNING, NEW YORK, ASSIGNOR TO CORNING GLASS WORKS,
A CORPORATION OF NEW YORK.

DESIGN FOR A HEADLIGHT COVER-GLASS.

52,384.

Specification for Design. Patented Sept. 10, 1918.

Application filed October 18, 1917. Serial No. 197,345. Term of patent 14 years.

To all whom it may concern:

Be it known that I, WILLIAM CHURCHILL, a citizen of the United States, residing at Corning, in the county of Steuben and State of New York, have invented a new, original, and ornamental Design for Headlight Cover-Glasses, of which the following is a specification, reference being had to the accompanying drawing, forming part thereof.

The figure is a front view of an automobile

headlight cover glass having my design applied thereto.

I claim:

The ornamental design for a headlight cover glass as shown.

WILLIAM CHURCHILL.

Witnesses:

HENRY PHELPS GAGE,
EMILIO PASCUCCI.
